UNITED STATES PATENT OFFICE.

JOSEPH FIEHLER, OF POTTER, NEBRASKA.

SCAFFOLD-JACK.

1,145,300.

Specification of Letters Patent.

Patented July 6, 1915.

Application filed October 12, 1914. Serial No. 866,380.

To all whom it may concern:

Be it known that I, JOSEPH FIEHLER, a native born citizen of the United States, residing at Potter, in the county of Cheyenne 5 and State of Nebraska, have invented new and useful Improvements in Scaffold-Jacks, of which the following is a specification.

The invention relates to a scaffold jack, comprehending a collapsible structure which 10 may be readily secured in position when desired to provide for the speedy erection of the scaffold.

The main object of the present invention is the provision of a scaffold jack or support 15 in which the parts are constructed to permit a convenient and speedy arrangement in scaffold supporting position and foldable into small compass when not desired for use.

The invention in the preferred form of 20 details will be described in the specification, reference being had particularly to the accompanying drawings, in which:—

Figure 1 is a perspective view of the improvement. Fig. 2 is a side elevation of the 25 same.

In constructing the improved jack, I provide a supporting bracket 1, comprising a plate-like member of substantial thickness having outstanding spaced ears 2 to receive 30 a supporting bolt or bar 3. The ends of the plate beyond the ears are preferably of double thickness and upturned at the ends so as to provide flanges serviceable to receive the blows of the hammer or the like in removing the bracket from its position on the wall.

Removably secured upon the bolt 3 are 40 hangers 4 comprising strips of appropriate length, having their respective ends given a half turn as at 5 and 6, so that the upper ends may be connected to the bolt, and the strips hang flat below the bracket. One of the hangers intermediate its ends is provided with a spacing bar 7 pivotally connected thereto at 8, the free end of the bar having a series of notches 9 adapted to engage a pin 10 projecting from the other hanger, whereby the lower ends of the hangers may be spaced apart as desired and

held in such spaced relation. The spacing 50 bar 7 is formed intermediate its ends with an opening 11 for a purpose which will later appear. Brace bars 12 are pivotally connected to the lower end 6 of the hanger bars, the upper ends of the brace bars being provided with a connecting pin 13. Floor bars 14 are pivotally supported on the bolts 3 of the bracket and are formed at their free ends with a series of notches 15, in one of which is adapted to coöperate with the pins or projections 13 of the brace bars.

In mounting the structure the bracket is firmly secured to the wall or other upright portion beyond which it is desired to erect the scaffold. In this position, the hangers 65 are pendant from the upright, and are secured against lateral swinging by a securing means such as a nail or the like, driven through the opening 11 in the spacing bar and into the structure. The brace bars are 70 extended outwardly to the desired distance and the floor bars interlocked therewith as described. The platform or parts forming the platform of the scaffold are supported directly upon floor bars 14.

From the above, it will be evident that the scaffold jack may be readily extended when desired for use and that the connections provide for a variety of adjustments. When not desired for use, the parts readily collapse, that is fold into a comparatively flat, small package. It is of course understood that any number of jacks may be used in supporting a particular scaffold, in accordance with the length requirements thereof.

What is claimed is:—

A scaffold jack including a bracket adapted to be secured to a structure and provided with spaced ears projecting at right angles to the plane of the bracket, a pivot bolt 90 uniting the ears, a floor bar removably mounted on said bolt, hangers pivotally mounted on the bracket intermediate the ears, a spacing bar pivotally connected to one hanger below the bracket and adapted 95 for adjustable connection to the other hanger, to adjustably space the lower ends of the hangers, brace bars pivotally con-

nected to the lower ends of the hangers, a bolt uniting the forward ends of the brace bars, the forward end of the floor bar being formed with a series of notches for coöperation with a bolt whereby to provide adjustable connection between the brace bar and floor bar.

Copies of this patent may be obtained for five cents each, by addressing the "Commissioner of Patents, Washington, D. C."

In testimony whereof I affix my signature in presence of two witnesses.

JOSEPH FIEHLER.
